UNITED STATES PATENT OFFICE.

THOMAS W. CHAMBERLAIN AND EDWARD L. AGAN, OF WHEELER'S MILL,
KENTUCKY.

STILL-FURNACE OR OTHER FLUE.

SPECIFICATION forming part of Letters Patent No. 517,404, dated March 27, 1894.

Application filed June 2, 1893. Serial No. 476,418. (No model.)

To all whom it may concern:

Be it known that we, THOMAS W. CHAMBERLAIN and EDWARD L. AGAN, citizens of the United States, residing at Wheeler's Mill, in 5 the county of Grayson and State of Kentucky, have invented certain new and useful Improvements in Still-Furnace or other Flues; and we do declare the following to be a full, 10 clear, and exact description of the invention, such as will enable others skilled in the art to which it appertains to make and use the same, reference being had to the accompanying drawings, and to the letters of reference marked thereon, which form a part of this 15 specification.

The special object of the invention is to so combine valves with a furnace that the heat may be controlled and regulated, thereby preventing a copper still from burning or 20 boiling over and enabling the operator to make one extra "run" each day, and rendering it unnecessary to draw the fire to make the still cool while it is being emptied and filled up.

25 Our valve is adapted for use on the furnaces of whisky or other stills and all kinds of flues for heating purposes.

Figure 1 of the drawings is a perspective view of a still-furnace provided with our invention; Fig. 2 a horizontal section thereof 30 and Fig. 3 a vertical section on the dotted line $\alpha\alpha$ of Fig. 2.

In the drawings, A represents the furnace with openings d in the top, B the still which is placed over the middle of the furnace, and C the outer casing between which and the still is left an annular space for the circulation of hot air around the still. In the bottom of this air-chamber D is a hole d communicating with the combustion chamber of the furnace and from it rises the inclined deflector E which extends up to the annular cover F. This causes the hot air to circulate around the still before it escapes through the outlet 40 f in cover F.

G is the still-cover having a pipe g through which the vaporized products of distillation pass. Over the furnace holes d works the slide-valve H so as to open or close communication with the furnace chamber, and also 50 with the waste pipe I, the hot air being thus allowed to enter chamber D to heat the still or up through the waste-pipe to cool it.

J is a slidevalve in the casing C which keeps out or lets in cold air to the chamber 55 D, this valve and the valve H being connected by rods j h with the same lever k fulcrumed on a projection i from the waste pipe and operated together so that the valve J may be opened whenever the valve H closes 60 the inner opening d .

What we claim as new, and desire to protect by Letters Patent, is—

The combination of the furnace A with the two openings d in the top, the superposed still 65 B, the case C arranged around the still to form an intermediate chamber D communicating by one of the openings d with the furnace chamber, the waste pipe I communicating by the other opening d with the furnace 70 chamber, the slide valve H covering the openings d at different times and the slide valve J adapted to cover or uncover an opening in the side of the case C, the said valves being so connected by suitable mechanism with the 75 same hand-lever whereby when there is a direct draft, the still is cooled; and when there is an indirect draft, the communication, between the chamber surrounding the still and the outer atmosphere, is closed by the valve 80 J all substantially as shown and described.

In testimony whereof we affix our signatures in presence of two witnesses.

THOMAS W. CHAMBERLAIN.
EDWARD L. AGAN.
